UNITED STATES PATENT OFFICE.

WILLIAM E. DUERSTEN, OF NEW CASTLE, PENNSYLVANIA.

DESIGN FOR A NON-SKID TIRE.

55,987.

Specification for Design.

Patented Aug. 10, 1920.

Application filed December 4, 1919. Serial No. 342,560. Term of patent 14 years.

To all whom it may concern:

Be it known that I, WILLIAM E. DUERSTEN, a citizen of the United States, residing at New Castle, in the county of Lawrence and State of Pennsylvania, have invented a new, original, and ornamental Design for Non-Skid Tires, of which the following is a specification, reference being had to the accompanying drawing, forming part thereof.

Figure 1 is a fragmentary plan view of a tire showing my new design; and

Fig. 2 is a cross sectional view thereof.

I claim:

The ornamental design for a non-skid tire as shown.

WILLIAM E. DUERSTEN.
